UNITED STATES PATENT OFFICE.

WILL K. MONROE, OF CLEVELAND, OHIO, ASSIGNOR TO THE BROWN HOISTING MACHINERY COMPANY, OF CLEVELAND, OHIO, A CORPORATION.

CAR-UNLOADING APPARATUS.

1,196,134.

Specification of Letters Patent. Patented Aug. 29, 1916.

Application filed September 23, 1915. Serial No. 52,188.

To all whom it may concern:

Be it known that I, WILL K. MONROE, a citizen of the United States, residing at the city of Cleveland, in the county of Cuyahoga and State of Ohio, have invented a new and useful Improvement in Car-Unloading Apparatus, of which a clear and exact description, with references therein to drawings that accompany and make a part 10 of the specifications, is hereinafter fully set forth.

The invention belongs to that class of mechanical instruments for unloading gondola or open-top railway cars, in the operation of which the loaded car is first raised, within a tower-like structure, to a predetermined point, and then, overturned upon and along the mouth of a chute which leads to a vessel or other receptacle below, and, thereafter, the load being thus discharged, by a reversal of the process, the emptied car is lowered to the base of the tower, from whence it is moved outwardly to make way for another car and load. Most apparatus 20 of this class is characterized by an L-shaped cradle to receive and sustain the car during the operative cycle, which cradle is alternately raised and lowered under the joint, or resultant effect of two oppositely related 25 motor forces, namely, one, consisting of a rope and sheave system actuated by a hoisting engine, and, the other, of a like system, actuated by a counterweight, the two systems being severally applied to the cradle, 30 and exerting their principal pull, at opposite sides of the same. As is manifest, the primary tendency of each of said forces, as applied, is to elevate the particular side of the cradle, where its force is principally 35 applied, and, in advance of the other side, and, therefore, toward overturning said cradle around such opposite side in each case. In consequence, a secondary and overturning movement of the cradle, around its 40 upright member or side, may be brought about, at any time, by simply stopping the travel upward of said side, under certain conditions, while the motive force at the other or inner side of the cradle is allowed 45 to continue with its normal hoisting and overturning tendency. A reversal or overturning of the cradle and its loaded car, has been effected heretofore in this manner by 50 locating stops at predetermined points in the path of travel of the vertical members 55 of the L-shaped cradle, in order that when these stops are encountered by said members, they will arrest any further travel upward of that side of the cradle, and, at the same time, serve as pivots around which, under 60 the influence of the force applied to the other and opposite side, the cradle will necessarily overturn. Several undesirable effects and conditions, however, are found to attend any sudden stoppage of the upward travel of the cradle in an apparatus of 65 the kind in question, by the interposition, as described, of fixed obstacles or stops to such movement, without at the same time cutting off the hoisting force. Besides a necessary 70 slowing up of the machine, as the cradle approaches the stops under the circumstances named, the shock due to the cradle's encounter with the stops, is necessarily severe, and the reaction from the same is injuriously 75 felt throughout the entire structure. So, too, the lifting power on the stopped side of the cradle, being still exerted against said obstacles to the normal and initial degree, 80 all parts involved are subjected thereby, to no purpose, to, and are kept under a maximum strain and tension during the dumping movement that ensues.

It is the design of the present invention to remedy the undesirable features above referred to, in prevailing types of car-unloading machines to the end, in particular, that the stops above referred to may be done away with entirely, and the cradle and load in the car carried by the same, may be brought 90 up within the tower structure to any desired point for discharge and there overturned, without any undue shock or strain during the process, or without serious waste 95 of motor energy.

In the accompanying drawings Figure 1 is an end view of a car-unloading apparatus, or tipple, where the overturning point of the cradle is fixed. Fig. 2 is a like view, where the overturning point is adjustable. 100 Fig. 3, is a sectional plan through the lines *a*, *a*, in Fig. 1. Fig. 4 is an enlarged end view of the so-called pan-girder, and associated parts when the cradle (indicated, in dotted lines in Fig. 1) is in overturning position and is latched against descent in such position. Fig. 5 is a sectional plan view, through the lines *b*, *b*, in Fig. 2. Fig. 6 is an enlarged end view of said pan-girder 105 and parts, (indicated in dotted lines in Fig. 110

2), when the cradle is in said latched position. Fig. 7 is a similar view to Fig. 6, with the cradle at its normal position, and unlatched, and, Fig. 8 is a plan of the latch-
5 engaging block on the cradle-pin.

In said figures, 1, represents a framework tower-structure, and 2 the usual L-shaped cradle therein. As will be understood by those familiar with the art, the
10 loaded car is brought in onto the cradle, and, is restrained thereon through all the subsequent movement for the purpose of raising, overturning and returning the car to normal place, by various familiar means,
15 and appliances, most of which are plainly shown or indicated in the drawings.

No detailed description of the apparatus is probably required other than of the principal or special parts, or features which concern the invention herein claimed, and which chiefly contribute to its operative value. These, for the most part, are as follows: Somewhat within the vertical portion 3 of the tower-structure 1, along and interiorly of each side thereof, are oppositely related pairs of guide-angles forming a guide or track 4, to receive sliding trunnion-blocks 5, on the ends of pins 6, which project laterally from each side of the upright member of the cradle 2. In the form of the invention disclosed in Fig. 1, the usual pan-girder 7, is permanently located across the outer face of said vertical portion, and at the predetermined height for the overturn. 30 This girder is shown, as thus fixed, to and between the corner-posts 8, in said tower-structure. The clevises of the counter-weight-ropes 9 and the engine-ropes 10, each of which ropes leads to its own motor forces 35 11 and 10^a respectively, are indicated as fastened to the cradle pins 6. The counter-weight ropes 9 extend, from their several clevises, attached to the cradle-pins, as said, upwardly to and around sheaves 13, at the 40 opposite corners of the tower-structure, to the traveling counterweight 11, on the exterior face of said structure opposite the cradle. The engine-ropes 10, likewise extend, in the usual course, from their clevises, 45 upwardly to and around sheaves, at the top of the tower, downwardly, to and around sheaves on the horizontal member of the cradle, upwardly, again, to other sheaves at the top, and, thence, downwardly to the 50 drum of the hoisting engine below.

At a point, in the downward path of travel of the counterweight 11, is located a stop 14 for the same, to arrest any further upward pull by the counter-weight upon the 55 cradle. The points for the location of the stops must, of course, vary, in particular cases, according to the relations to and connections of the rope 9 with the weight 11, and the cradle 2, but in every case, such 60 point must be at the place in said path, at

which the weight arrives when the cradle itself, under the joint hoisting action of weight and engine reaches the end of its upward travel and place for overturning.

To guard against a descent of the car in 70 its inverted position, some special provision is desirable, and, in the figures, one form of such a provision is shown. It is in the form of a flat-casting or latch 16, pivoted, near its lower end at 17, to the ends of pan-girder 7. 75 Said casting is held, in a normal advanced position around its pivot, by means of a spring-connection 18, anchored to the pan-girder. The trunnion-blocks 5 are enlarged throughout their length, on the sides nearest 80 the pan-girder, into cam-like protuberances 19, to engage the latch as the cradle approaches the dumping point.

The lower portion of the blocks are recessed from the protuberances 19, to correspond with the contour of the upper end of the latches 16 (Figs. 6 and 7), which latter carry projections or lugs at their inner ends, to bring up against limiting blocks or stops 26, located on the girder for the purpose. Near the upper end of the vertical member of the cradle, at suitable distances from the cradle-pins to encounter the latches 16, as the cradle returns to the normal, and shift said latches around their pivot and thereby release the same from their engagement with the trunnion-blocks 5, are secondary latch-actuating blocks 20. A release having been thus effected, the cradle is free to descend, along the guides 4, to its normal 100 place in the tower.

Under certain conditions, in the operation of a machine of the kind under consideration, it becomes desirable to change the height at which the dump is to be made. 105 The variation in the level of tides, or in the vessel itself, under its growing load, are familiar instances or occasions for this need, and, I have, accordingly added an adjustability of this nature, to the device already 110 explained, by the features set forth in Figs. 2, 5, 6 and 7. To this end, the pan-girder 29, instead of being fixed at some predetermined point in the tower, as is the girder 7; is made movable, up and down in the 115 same, by so arranging that the girder is supported, at its ends, by and upon vertical screw shafts 21, which fit into corresponding nuts 22, located at the ends of the girder for the purpose. The shafts are threaded to an extent corresponding with the limit for the travel of the cradle, in any given situation, and are connected up with the engine through a train of gears and shafting, as indicated by the dotted lines (Fig. 2). 125 In the modification in question, the stops 28, for the counterweight, must also be movable and to a degree that shall vary and correspond with any movement of the pan-girder 29. An additional rope 24 is 130

therefore connected, for this purpose, to the ends of the pan-girder 29, as by clevises at 25, (see Figs. 5 and 6,) and carried up over the sheaves 43 downwardly, loosely 5 through the counterweights 27, to a freely movable stop 28. It is evident that, by this means, as the pan-girder, and consequent overturning point for the cradle, are adjusted from one point to another, by the rotation of the threaded shafts 21, the stop 10 28 to the further descent of the counterweights 27, will also move up or down to a corresponding extent, and, that the necessary relative distance of the same, for the 15 due arrest of the counterweight 27, will always be maintained. Of course, the means just shown for thus insuring a correspondence of movement between the adjustable pan-girder 29, and the stop 28 for the counterweight 27, may be varied without thereby departing from what is intended to be claimed herein; any suitable means for obtaining such a correspondence, as, for instance, by substituting for the rope 24 and 20 its connections, a shaft and gear to effect a movement of said stop in unison with the movement of the pan-girder 29, will equally be within the invention.

Having thus described said invention, 30 what I claim and wish to protect by Letters Patent is:—

1. In a car-dumping apparatus, the combination with a cradle, guides for directing the vertical and pivotal movement of said 35 cradle, a hoisting drum, and a cable connected therewith and with both sides of the cradle, a cable attached to the outer side of the cradle, a counterweight on said last mentioned cable, and a stop at a suitable 40 point in the path of the counterweight to be engaged by said counterweight when the cradle has been raised to a predetermined height in said guides by the joint hoisting action of said drum and counterweight, substantially as shown and described.

2. In a car-dumping mechanism, the combination, with a tower-structure, of oppositely related guides thereon, a cradle having a vertical and a horizontal member 45 ably mounted in said guides, means for applying a hoisting force to said cradle upon its horizontal member, a counterweight system adapted, normally, to exert a hoisting force upon said cradle upon its vertical member, and a stop at a suitable point, in the path of the counterweight in said system, to be engaged by said counterweight in its normal course, when the cradle has been hoisted, in said guides, by said forces 55 to a predetermined point, substantially as shown and described.

3. In a car-dumping mechanism, the combination, with a tower-structure, of oppositely related guides thereon, a cradle, having a vertical and a horizontal member, slid-

ably mounted in said guides, a hoisting drum, and a cable connected therewith and with said horizontal member, a cable attached to said vertical member, a counterweight on said last mentioned cable, a pan-girder movably mounted on said structure, 70 in vertical guides provided for the purpose, an adjustable stop to the descent of said counterweight in its normal course, and means, respectively, for moving said girder, 75 at will, from one point to another in said guides, and correspondingly, moving said stop, substantially as shown and described.

4. In a car-dumping mechanism, the combination, with a tower-structure, of oppositely related vertical guides thereon, a cradle, having a vertical and a horizontal member, movably mounted in said guides, a hoisting drum and a cable connected therewith and with said horizontal member, a 80 cable attached to said vertical member, a counterweight on said last-mentioned cable, a movable stop, in the downward path of said counterweight, at a point to be encountered by the counterweight when the cradle 85 has been hoisted in its guides to a predetermined point, a vertically movable pan-girder on said structure, and means for moving said girder and said stop, in unison one with the other, from one predetermined 90 point to another, substantially as shown and described.

5. In a car-dumping mechanism, the combination, with a tower-like structure, of oppositely related vertical guides therein, a 100 cradle, having a vertical and a horizontal member, movably mounted in said guides, a hoisting drum and a cable connected therewith and with said horizontal member, a cable attached to said vertical member, extending upwardly to and around sheaves on said structure provided for the purpose, 105 downwardly to a counterweight movably mounted on said structure on the side thereof opposite to the cradle, a vertically adjustable pan-girder, on said structure upon the other side, a cable attached thereto, extending upwardly to and around sheaves on said structure provided for the purpose, 110 downwardly, below said counterweight to a movable stop on said opposite side, and means for moving said pan-girder vertically from one point to another upon the side where located, substantially as shown and described.

6. In a car-dumping mechanism, the combination, with a tower-structure, of guides thereon for directing the vertical and pivotal movements of a cradle movably mounted in said guides, a hoisting drum, and a cable connected therewith and with both sides of the cradle, a cable attached to the outer side of the cradle passing upwardly to and around sheaves on the structure above, downwardly to a traveling counter- 125 130

- weight on the opposite side of said structure, a stop on said last named side below and in the path of said structure at a suitable point to be engaged by the counter-
5 weight when the cradle has been hoisted to a predetermined point, together with suitable means for automatically locking the cradle at said point against descent during the overturning movement of the same, and
10 of automatically releasing said cradle, from said locked position, when it has thereafter regained its normal position within the structure, substantially as shown and described.
- 15 7. In a car-dumping mechanism, the combination, with a tower-structure, of guides thereon for directing the vertical and pivotal movements of a cradle movably mounted in said guides, a hoisting drum, and a cable connected therewith and the inner 20 side of the cradle, a cable attached to the outer side of the cradle passing upwardly to and around sheaves on the structure above, downwardly to a traveling counter- 25 weight on the opposite side of said structure, suitable means for automatically locking the cradle at said point against descent during the overturning movement of the same, and of automatically releasing said cradle from said locked position, when it 30 has thereafter regained its normal position within the structure, substantially as shown and described.

WILL K. MONROE.

In presence of—

L. P. LIPPS,
C. S. MALTBIE.
